Attorney

UNITED STATES PATENT OFFICE.

NELLY NELSON SCHNEIDER, OF NAUVOO, ILLINOIS.

FLOWER HOLDER.

Application filed March 27, 1925. Serial No. 18,812.

To all whom it may concern:

Be it known that I, NELLY NELSON SCHNEIDER, a citizen of the United States, residing at Nauvoo, in the county of Hancock and State of Illinois, have invented certain new and useful Improvements in a Flower Holder, of which the following is a specification.

This invention relates to improvements in flower holders and is more particularly adapted to a basket for holding flowers, the basket being principally adapted for use upon graves and cemetery lots.

One of the important objects of the present invention is to provide a flower holder wherein means is associated with the basket for supporting the same in an upright position on the ground so that the accidental displacement of the basket is prevented.

A further object of the invention is to provide a flower holder of the above mentioned character wherein a plurality of anchoring pins or stakes are associated with the base of the basket, the stakes being adapted to enter the ground so that the base of the basket will rest rigidly on the surface.

A still further object is to provide a flower holder of the above mentioned character which is simple in construction, inexpensive, strong and durable and further well adapted to the purpose for which it is designed.

Other objects and advantages will become apparent during the course of the following description.

In the accompanying drawing, forming a part of this specification, and in which like numerals designate like parts throughout the same:

Figure 1 is a side elevation of the flower holder embodying my invention showing the manner in which the anchoring pins or stakes are associated with the base of the basket, and

Figure 2 is a plan view of the base.

In the drawing, wherein for the purpose of illustration is shown the preferred embodiment of my invention, the numeral 1 designates generally the basket, the body 2 thereof being formed of woven material in the manner well known in the art. The base of the basket comprises a substantially cir-

cular disk. The base is provided with an annular series of spaced openings 4 adjacent the peripheral edge thereof whereby the disk 5 may be interwoven to the bottom of the body 2 by the vertically arranged strands 5 of the woven material from which the body is formed.

The base 3 is further provided with the spaced laterally extending ears 6, each of which is provided with an opening 7, and the purpose of these ears will hereinafter be more fully described.

The basket is adapted to be supported in an upright position on the ground through the medium of the anchoring pins or stakes 8. These anchoring pins or stakes extend through the openings provided in the respective laterally extending ears formed on the base and enter the ground so that the heads 9 formed on the upper ends of the anchoring pins or stakes engage the upper surface of the base and enable the bottom face of the base to rest on the surface of the ground.

The provision of a flower holder of the above mentioned character enables the basket to be supported in an upright position on the ground against accidental blowing over by the wind, or against the basket being knocked over by small animals.

A basket of the above mentioned character is particularly adapted to be used for holding flowers on a grave or cemetery lot, although it is to be understood that I do not wish to limit myself to the use of the present invention.

The simplicity in which my improved flower holder is constructed enables the same to be readily and easily set up in position for use, and may furthermore be readily and easily removed by removing the anchoring pins or stakes.

While I have shown the preferred embodiment of my invention, it is to be understood that various changes in the size, shape and arrangement of parts may be resorted to, without departing from the spirit of the invention and the scope of the appended claim.

Having thus described the invention, what I claim as new is:—

A flower holder comprising a basket, the

bottom of said basket comprising a disk-like member, laterally extending ears formed on said disk at spaced intervals, each of said ears being provided with an opening, and a plurality of elongated anchoring pins extending through the openings in the respective laterally extending ears and adapt-

ed to enter the ground for supporting the basket in an upright position on the ground, and heads formed on the upper ends of the 10 anchoring pins and engaging the upper face of the respective ears.

In testimony whereof I affix my signature.

NELLY NELSON SCHNEIDER.
